Fig. 2

To all whom it may concern:

Be it known that I, Robert O. Fletcher, a citizen of the United States, residing at Ashland, county of Middlesex, Commonwealth of Massachusetts, have invented a new, original, and ornamental Design for a Clock, of which the following is a specification, reference being had to the accompanying drawing, forming a part thereof.

In the drawing:

Fig. 1 is a front perspective view of a clock illustrating my new design.

Fig. 2 is a perspective view partly in section illustrating my new design.

The opposite side of the illustrated clock embodying my invention is the same in appearance as the side shown, and the back thereof is substantially plain having the usual adjusting knobs extending therefrom.

I claim:

The ornamental design for a clock, as shown and described.
